Primary Examiner — Wan Laymon(57) **CLAIM**

The ornamental design for an oral care device, as shown and described.

DESCRIPTION

FIG. 1 is a front top left perspective view of an oral care device according to a first embodiment of the new design; FIG. 2 is a front top right perspective view thereof; FIG. 3 is a front bottom left perspective view thereof; FIG. 4 is a front bottom right perspective view thereof; FIG. 5 is a rear perspective view thereof; FIG. 6 is a front view thereof; FIG. 7 is a rear view thereof; FIG. 8 is a left-side view thereof; FIG. 9 is a right-side view thereof; FIG. 10 is a top view thereof; and, FIG. 11 is a bottom view thereof.

The broken lines illustrate portions of the oral care device that form no part of the claimed design.
